UNITED STATES PATENT OFFICE.

HARRY J. SCHADE, OF LOS ANGELES, CALIFORNIA.

MOLDING-MACHINE.

No. 828,056.

Specification of Letters Patent.

Patented Aug. 7, 1906.

Application filed October 5, 1905. Serial No. 281,498.

To all whom it may concern:

Be it known that I, HARRY J. SCHADE, a citizen of the United States, residing at Los Angeles, in the county of Los Angeles and State of California, have invented new and useful Improvements in Molding-Machines, of which the following is a specification.

My invention relates to a machine for molding artificial-stone blocks or bricks or other material, and the object thereof is to provide a machine for that purpose which can be quickly adjusted to make blocks of different sizes and in which the molded material may be quickly and easily removed from the machine. I accomplish these objects by the machine described herein and illustrated in the accompanying drawings, in which

Figure 1 is a side elevation of my improved machine. Fig. 2 is a plan of the machine. Fig. 3 is an end elevation. Fig. 4 is a section on line 4-4 of Fig. 2. Fig. 5 is a partial side elevation, partly in section, of the modification of the mold-box. Fig. 6 is a plan of the parts shown in Fig. 5. Fig. 7 is a cross-section of the mold-box shown in Fig. 6. Fig. 8 is a perspective of a core-block. Fig. 9 is a detail of a bushing.

In the drawings, 10 is the bed-plate, which is preferably made of cast-iron. The central portion 10' of the bed-plate is wider than the end portions and is also raised, as best shown in Figs. 1, 3, and 4. At the ends of the raised portion and extending transversely of the bed-plate are the dovetail guideways 11, which receive and guide the bottom of legs 12' of benches 12, which support the die-plate 13 of the mold-box in which the stone or other material is formed in shape. In these guideways are also received the legs 14 of the turn-table, which will be more fully described hereinafter. The mold-box consists of the channel-shaped cast-iron sides 15 and the cast-iron end pieces 16. These end pieces are as wide as the box is required to be for making stone of the maximum width. At the top and bottom on both sides they are provided with projecting lugs or ears 16', which are provided with slots 17, through which pass bolts 18, which unite the sides of the box to the adjusting-bars 19, of which there are two at each end. A shaft 20, screw-threaded at its ends, passes through these adjusting-bars in threaded contact therewith at one end of the box. This shaft also passes through a box-shaped lug 21, in which it is

revoluble but not longitudinally movable, collars 22 being secured thereto to prevent its longitudinal movement through the lug. This lug is secured to the end piece and is preferably cast integral therewith. Shaft 20 has an operating-crank 23, by means of which it is rotated. On this shaft is also mounted a sprocket-wheel 24, which is connected by sprocket-chain 25 with sprocket-wheel 26, mounted on shaft 27, which shaft passes through a lug 28 similar to lug 21, secured to the other end plate, and is screw-threaded at its ends the same as shaft 20. These shafts have right-hand threads at one end and left-hand threads at the other end, and when rotated they cause the sides of the mold-box to approach each other or to recede from each other, as desired, within the limit of the lengths of the slots in the ears of the end pieces. In lug 21 are secured the internal-screw-threaded bushings 29, a detail of which is shown in Fig. 9. Through these bushings and in threaded contact therewith passes the threaded shaft 30, which is provided with a collar 31, which rests upon the cross-bars 32 of the guide-frame 33, in which lug 21 is guided in its vertical movement. On the lower end of shaft 30 and below the cross-bar 32 is a bevel-gear 34, which meshes with the bevel-gear 35, mounted on shaft 36. On the outer end of the shaft 36 is sprocket-wheel 37, which is connected by sprocket-chain 38 with sprocket-wheel 39, mounted on shaft 40, which shaft is revolubly mounted on the side of the guide-frame 33. On the end of shaft 40 is a crank 41, by means of which motion is imparted to the sprocket-wheel. On the inner end of shaft 36 is a bevel-gear 42, which meshes with the bevel-gear 43 on the lower end of shaft 44. Shaft 44 is threaded and passes through threaded bushings 44', which are secured in lug 28 in the same manner that bushings 29 are secured in lug 21.

For the purpose of making an expandible machine I cut shaft 36, as shown in Fig. 1, and provide a coupler-sleeve 46 and secure the shaft to the sleeve by bolts 47, which pass through holes therein. By making holes 48 near the end of the cut section it is evident that shaft 36 can be lengthened, and by making slots 49 in the bed-plate, through which bolts 50 pass, the guide-frames 33 may also be adjusted to lengthen or shorten the machine. Lugs 21 and 28 are provided with

slides 51, which project into vertical grooves 52 in the guide-frame 33.

In the operation of my machine by the use of crank 23 the sides of the mold-box are adjusted to the required thickness of stone to be made, and a die-plate 13 of a width corresponding with said thickness is placed upon the supporting-benches, which are moved by hand in guideways 11 until they are in the proper position to support the die-plate, one pair of legs being under one edge thereof and the other pair of legs under the other edge at a sufficient distance from the edge to properly support it. When an ornamental face is desired, a facing-block 53, containing the design for the face of the stone, is placed upon said die-plate, as shown in Fig. 4. By means of crank 41 the sides and ends of the mold-box are then adjusted so that they project a sufficient distance above the facing-plate to form a stone of sufficient thickness. Fine concrete 54, forming facing material, is then placed upon the facing-plate and tamped in the usual manner, after which the box is filled up with coarser concrete 55 until the top of the box is reached. As soon as the box is filled to the top and the material properly tamped therin by means of crank 41 the sides and ends of the box are lowered through the connecting mechanism until the same pass below grooves 56 in the top of the supporting-benches 12. The side of the mold-box adjacent to the supporting-frame at the bottom thereof carries an interference-lug 57, which engages an arm 58 on shaft 59, and as the side moves downwardly causes the partial rotation of shaft 59. Shaft 59 has secured thereto at each end thereof shifting arms 60, the upper ends of which bear against a rod 61. At the ends of rod 61 and rigidly secured thereto are L-shaped frames 62, which form a part of the turn-over, the perpendicular members of which are provided with handles 63. Before the sides and ends of the mold-box are turned downwardly a bottom board 64 is placed against the vertical members of the turn-over. As soon as the lug 57 engages arm 58 the shifting arms 60 move the turn-over and carry the bottom or horizontal members thereof through slots 53 in the supporting-benches until the bottom board 64 contacts with the formed stone. At this time lug 57 disengages from arm 58 and passes below it, when the shifting arms 60 fall back to their original position, resting against stop-pins 65 in the turn-table. The operator then seizes handle 63 and turns the turn-over down, so that the bottom board is underneath the stone. The cross-bar of the turn-over is so located that the front edge of the vertical member is on a line with the back edge of the cross-bar, so that the bottom board will touch its full width at one time and rest upon bars 66 of the turn-table. The stone is re-

moved therefrom, and the guide-plate and facing-plate are removed from the stone and replaced upon the supporting-benches and the sides and ends returned to a position to form a new stone. When it is desired to form double-face stone, I hinge a cover 67 to one of the end plates, as shown in Figs. 5 and 6. I then form the first face in the same manner as the single-face stone and fill in coarse concrete to near the top of the box, leaving sufficient room therein to place the facing material 68 in the box and also to place the facing-plate 69 therein. I then place die-plate 70 on top of the facing-plate and bring the cover over to rest upon the die-plate. I then secure the cover to the box by means of clamping-frames, which are composed of cross-bars 71, on the ends of which are depending arms 72, which have inwardly-projecting lugs 72', which pass under lugs 85 15', which are preferably cast integral with the sides. The opposing faces of the respective lugs are preferably wedge-shaped, so that the clamps may be firmly secured to the sides. On shaft 30 I screw a nut 73, which is adapted to engage cover 67 to stop its downward movement, which is accomplished by turning crank 41 to cause the sides and ends of the box to descend, thereby compressing the concrete until the upper face 95 is properly formed. Nut 73 could be omitted, if desired; but it forms a convenient guide to indicate the amount of pressure to be put upon the stone to properly form the second face thereon. By removing pins 74 from the hinges which secure the cover to the end plate the cover may be removed and the machine used for making single-face stone. When it is desired to form hollow stones; I place a core-block 75 in the concrete, as shown in Fig. 4. This core-block consists of a wooden center 75', in which are bored holes 76 to provide means for removing the core-block from the finished stone. The wooden center is faced with a metallic facing 75", which may be of sheet metal, the same being brazed at its edges and the wooden center driven therein. The core-block is slightly tapered to aid in its removal from the stone. By forming the core-block with a wooden center lightness and strength are secured, and by casing it with the metal smoothness of surface is obtained and the wooden center is prevented from getting wet and swelling.

Should it be desired to hold the sides and ends of the mold-box at any particular elevation between the extreme limits of their movement I provide a dog 76, which engages a ratchet-wheel 77 on shaft 40, so that by throwing the dog into engagement with the ratchet-wheel the downward movement of the sides and ends of the mold-box may be stopped at any point.

Having described my invention, what I

claim as new, and desire to secure by Letters Patent, is—

1. In a block-forming machine a bed-plate having transverse guideways therein; supporting-benches having legs resting in and guided by said guideways; a die-plate resting upon said benches, side and end plates adjustably secured together and adapted to be moved vertically upwardly and downwardly past said die-plates, said die-plate, sides and ends forming a mold-box; and means to move said side and end boards comprising a shaft mounted in bearings in the bed-plate; two bevel-gears secured upon said shaft, one at each end thereof; two vertical shafts each carrying bevel-gears at their lower end and having their upper end screw-threaded, said bevel-gears meshing with the gears on the horizontal shaft; bearings secured to the center of the end of the mold-box and having vertical threaded openings extending therethrough for the reception of said threaded shafts; vertical guide-frames for guiding said bearings; and means for rotating said horizontal shaft.

2. In a block-forming machine a mold-box composed of end plates having bearing-lugs centrally secured upon their outer faces; side plates adjustably secured to said end plates, said side and end plates forming when adjusted the sides and ends of the mold-box; a die-plate adapted to form the bottom of the mold-box; adjustable means for supporting said die-plate in position while the block is being formed; guide-frames for receiving and guiding vertically the bearing-lugs of the end plates; screw-threaded shafts passing vertically through said bearing-lugs in threaded contact therewith and revolvably mounted in cross-bars in the guide-frame; and means to cause the simultaneous revolution of said vertical shafts.

3. In a molding-machine a mold-box composed of a die-plate forming the bottom thereof; two end plates having bearing-lugs in the center of the outer surfaces thereof and having slots near the corners thereof; vertical adjusting-bars on the exterior sides of said end plates; bolts passing through said adjusting-bars and through the slots in the end plate and secured to the side plates; screw-threaded horizontal rods passing through said adjusting-bars in threaded contact therewith and having a right-hand thread on one end and a left-hand thread on the other end thereof, said rods also passing through said bearing-lugs revolvably therein and having means secured thereto to prevent the longitudinal movement of the rods in the lugs.

4. In a block-forming machine a bed-plate

having transverse guideways therein; supporting-benches having lugs resting in and guided by said guideways, said supporting-benches having transverse slots in the top thereof; a die-plate resting upon said benches; end plates having bearing-lugs in the center of the outer surfaces thereof and having slots near the corners thereof; vertical adjusting-bars exterior said end plates at the ends thereof; side plates between said end plates secured to the adjusting-bars by bolts passing through the slots in the end plates; screw-threaded horizontal rods passing through said adjusting-bars in threaded contact therewith and having a right-hand thread on one end and a left-hand thread on the other end, said rods also passing through said bearing-lugs revolvably therein and having means secured thereto to prevent the longitudinal movement of the rods within the lugs; means to cause the simultaneous movement of said horizontal rods; screw-threaded shafts passing vertically through said bearing-lugs in threaded contact therewith; means to cause the simultaneous revolution of said vertical shafts; means to support said vertical shaft; means to guide the bearing-lugs of the end plates vertically; a turn-table composed of two L-shaped end pieces connected by a transverse bar; a supporting-frame upon which said turn-table rests; and means to move said turn-table into engagement with the stone block upon the lowering of the sides and ends below the block.

5. In a block-forming machine a turn-table composed of two L-shaped end pieces connected by a transverse bar; a supporting-frame upon which said turn-table rests; a removable bottom board on said turn-table; and means to move said turn-table and bottom board into engagement with the stone block upon the lowering of the sides and ends below the block.

6. In a molding machine a mold-box composed of vertically-movable side and end pieces; a stationary closure for the bottom of the opening between the side and end pieces; a removable lid secured to the top of said side and end pieces; and means to move said side and end pieces and lid toward the bottom closure.

In witness that I claim the foregoing I have hereunto subscribed my name this 29th day of September, 1905.

HARRY J. SCHADE.
